UNITED STATES PATENT OFFICE.

CHARLES S. HAZLETT, OF BOONE, IOWA, AND JOHN WEST, OF CHICAGO, ILLINOIS, ASSIGNORS TO BARNHART BROTHERS & SPINDLER, OF ILLINOIS.

DESIGN FOR A FONT OF PRINTING-TYPE.

SPECIFICATION forming part of Design No. 20,514, dated February 10, 1891.

Application filed December 31, 1890. Serial No. 376,400. Term of patent 14 years.

To all whom it may concern:

Be it known that we, CHARLES S. HAZLETT, a citizen of the United States, residing at Boone, county of Boone, and State of Iowa, and JOHN WEST, a citizen of the United States, residing at Chicago, county of Cook, and State of Illinois, have invented and produced a new and original Design for a Font of Script Type, set forth in the following specification, reference being had to the accompanying typographical impressions, forming a part thereof.

This design comprises upper and lower case letters, figures, points, character &, dollar-mark, and vertical connection-strokes. The general style of the font is plain, without flourish or unnecessary "movement" or appendages. The lower-case letters especially are quite extended, producing a square open appearance, the height and breadth of each single element, as o, and the like element of a, b, d, p, the element which is repeated in m, and its like element in n and v, and the element in u and w being about equal. The lower-case letters and figures are almost devoid of shades, lines being light, but not quite hair-lines, almost imperceptibly thickened on some of the downstrokes. Capitals are slightly but obviously shaded on downstrokes. The inclination of the letters is forward at a very small angle, just avoiding the appearance of being perfectly upright, thus adding to the

"square" appearance. The letters commence and terminate without special provision for connecting with preceding and succeeding letters—that is, no special initial or terminal strokes are appended to the letter proper. The composed matter has therefore a disjoined appearance as distinguished from the appearance of a continuous line or "pen-trail" in each word. Exceptions to this rule are in some instances produced by use of the vertical circumflex connecting-stroke to join a preceding letter which terminates forwardly at the bottom to a succeeding letter which commences with a forward stroke at the top— as, for example, a, followed by n or m.

We claim—

The design for a font of script type herein shown and described.

In testimony whereof we have hereunto set our hands, CHAS. S. HAZLETT at Boone, Iowa, the 26th day of December, 1890, and JOHN WEST at Chicago, Illinois, the 23d day of December, 1890.

CHAS. S. HAZLETT.
JOHN WEST.
